UNITED STATES PATENT OFFICE.

JOSEPH L. WALKER, OF BATON ROUGE, LOUISIANA, ASSIGNOR TO K-D BARREL AND HAMPER CO., OF BATON ROUGE, LOUISIANA.

VENEER DRUM OR THE LIKE.

Application filed June 11, 1921. Serial No. 476,856.

To all whom it may concern:

Be it known that I, JOSEPH L. WALKER, a citizen of the United States, residing at Baton Rouge, in the parish of East Baton 5 Rouge and State of Louisiana, have invented a new and useful Veneer Drum or the like, of which the following is a specification.

This invention relates to a drum or the 10 like formed of veneer, one of its objects being to provide a structure of this character having simple and efficient means whereby the heads can be connected to the wall of the container without the necessity 15 of grooving the same, there being simple and efficient fastening devices which constitute supports for the heads and also constitute means for fastening the heads detachably in position.

20 Another object is to provide fasteners which can be cheaply produced from strips of sheet metal, can be applied readily, and will constitute efficient means for securely holding the heads in place.

25 A still further object is to provide a container which is thoroughly ventilated.

With the foregoing and other objects in view which will appear as the description proceeds, the invention resides in the combination and arrangement of parts and in the details of construction hereinafter described and claimed, it being understood that, within the scope of what is claimed, changes 35 in the precise embodiment of the invention shown can be made without departing from the spirit of the invention.

In the accompanying drawings the preferred form of the invention has been shown.

40 In said drawings

Figure 1 is an elevation of a drum or container embodying the present improvements.

Figure 2 is a plan view thereof.

45 Figure 3 is an enlarged section on line 3—3, Figure 2.

Figure 4 is a detail view of the blank from which the fasteners are formed.

50 Referring to the figures by characters of reference 1 designates the strips of material forming the staves of the drum, these strips being suitably connected at their ends or at other points by hoops 2 and the strips being preferably separated so as to allow air to circulate between them. The heads of 55 the drum can be of any construction desired

although preferably made of upper and lower layers of strips of veneer indicated at 3, the strips of one layer being spaced apart and placed transversely of the spaced strips of the other layer so that small ventilating 60 openings 4 thus occur between the points where the strips are crossed.

For the purpose of holding the heads in the drum there are provided fastening devices of simple construction. Each of these 65 fastening devices is formed from a blank of thin sheet metal in strip form as shown in Figure 4, these blanks being preferably cut from an elongated strip or ribbon so that each blank has a rounded end 5 and a recessed end 6, the recess forming side prongs 7. Spaced openings 8, 9 and 10 are formed in the blank. After the blank has been cut

it can be bent to proper shape with the prongs 7 bent at right angles and that portion of the blank between the openings 8 and 9 partly folded to present a shoulder 11 and an inclined supporting portion 12. With the blank thus shaped it is fastened 70

within the container by driving the prongs 7 into one of the strips 1 as shown in Figure 3 and then fastening the blank by driving brads 13 or the like through the openings 8 and 9 and into the container. Thus the

shoulder 11 will be supported within the 75 container and inwardly from the end of said container. After a desired number of fasteners have thus been secured the head 3 can be placed in the container so as to rest at its margin on the shoulders 11. The up- 80

wardly projecting end of the fastener which up to this time has been projecting beyond the container as shown by dotted lines in Figure 3, can then be bent down onto the head 3 and fastened thereto by means of a 85 brad 14 or the like. Thus the head will be securely held in place but can be removed readily simply by withdrawing the brad 14 of each fastener and bending the outer end of the fastener upwardly and outwardly to 90

the position shown by dotted lines in Figure 3.

95 It will be noted that by providing a fastener such as described it becomes unnecessary to groove, or otherwise specially prepare the strip 1 or the head 3 and the head can be readily inserted into the container and secured by means of the fastener.

100 What is claimed is:

The combination with a container, of 110

means for fastening a head thereto, said means comprising a single strip of bendable metal having a recess in one end forming spaced prongs, said prongs being extended 5 at right angles from the strip for insertion into the wall of the container, an offset intermediate portion formed by the strip and constituting a head supporting shoulder and an inclined brace for the shoulder, one 10 end of the strip being bendable onto the supported head to hold it on the shoulder, and fastening means extending through the strip between the prongs and the brace and into

the wall of the container, said prongs constituting means for holding the wall against 15 splitting by the fastening means, and a fastening device insertible through the bendable end of the strip for fastening it to the supported head.

In testimony that I claim the foregoing 20 as my own, I have hereto affixed my signature in the presence of two witnesses.

JOSEPH L. WALKER.
